UNITED STATES PATENT OFFICE

FRIEDRICH WEMPE AND HEINRICH PEPERKORN, OF CASSEL-WILHELMSHOHE, GERMANY, ASSIGNORS TO SCHMIDT'SCHE HEISSDAMPF-G. M. B. H., OF CASSEL-WILHELMSHOHE, GERMANY, A CORPORATION OF GERMANY

BOILER IN WHICH THE STEAM IS GENERATED INDIRECTLY

Application filed October 7, 1927, Serial No. 224,690, and in Germany November 6, 1926.

Our invention relates to boilers in which the steam is generated according to the indirect method and is specially suitable for those working with pulverized coal.

5 In known forms of boilers using pulverized coal, the steam is generated according to the direct method, such boilers in general being constructed by the simple addition of a combustion chamber to the boiler proper. These

10 boilers, however, occupy considerable space and in particular they are of great height as in most cases the flue leading from the combustion chamber is vertical and is arranged either directly above or above and to one side 15 of the combustion chamber.

A main object of the present invention is to provide an improved boiler of the kind indicated which shall be free from the objections above pointed out.

20 With such an object, the present invention consists in a boiler generating steam according to the indirect method, in which the heat-receiving surface of the heat-carrier tube system is divided into two juxtaposed parts, of

25 which the one part, which is preferably arranged to form the side walls, rear wall and roof of the combustion chamber, receives heat by radiation while the other part receives heat by contact with the hot gases and is ar-

30 ranged in a horizontal flue connecting the combustion chamber to a vertical flue in which are disposed a steam superheater, a feed-water heater and preferably also an air preheater.

35 Due to the new arrangement of the heating surface of the heat-receiving tubes of the heat-carrier system serving for the indirect generation of the steam, a very compact and low form of boiler is obtained. The improved

40 boiler, consisting essentially of the upper drum, or of several upper drums, the heat-carrier tube system and the combustion chamber, forms an organic unit, in which the tube

45 system lies in and behind the combustion chamber while the upper drum lies directly above this chamber and above the horizontal flue issuing therefrom. The space beneath this horizontal flue is preferably formed as a

50 passage to provide access to the individual

parts of the evaporating or preheating systems.

In addition it is preferable to provide between the horizontal flue and the vertical flue a cooled bridge in connection with which a 55 damper is provided for regulating the passage of the hot gases to the superheater.

In the drawings, one form of the improved boiler is shown by way of example.

Figure 1 is a longitudinal section through 60 the boiler on the line I—I of Figure 2, while Figures 2, 3 and 4 are respectively cross-sections on the lines II—II, III—III and IV—IV of Figure 1.

According to the form illustrated, the 65 brickwork, 1, of the boiler designed for burning pulverized coal, surrounds a burner chamber, 2, connected by way of a combustion chamber, 3, to a horizontal flue, 4, and a vertical flue, 5, air inlet openings, 6, being 70 provided in the front wall of the burner chamber, 2. Above the brickwork, 1, lie two drums, 7 and 8, in which the working steam is generated by indirect heating. For this purpose heating serpentines, 9, are arranged 75 in the water space of the drums, these serpentines giving up heat obtained from the heat-receiving tubes of the heat-carrier system to the water in the drums. The serpentines, 9, are connected by distributor or collector headers, 10, to the heat-receiving tubes of the heat-carrier system, these heat-receiving tubes being divided into two parts of

80 which one receives heat by radiation, the other by contact with the hot gases. The 85 part receiving heat by radiation is formed by tubes, 11, which are arranged to form the side walls, the rear wall and the roof of the combustion chamber, while the part in contact with the hot gases is formed by the 90 tubes, 12, lying in the horizontal flue, 4, issuing from the combustion chamber, 3. The tubes, 11, which are in two series lying adjacent to the rear wall, 13, of the combustion chamber as shown in Figure 3, are bent into 95 staggered zigzags reversely disposed in relation to one another so as to cover the rear wall, 13, as far as possible. The tubes, 12, lying in the horizontal flue, 4, are also bent into zigzags similarly disposed in relation 100

to one another so as to take full advantage of the eddying of the combustion gases from the point of view of efficient heat transfer-
ence.

5 Below the burner chamber, 2, and the combustion chamber, 3, is arranged a cooled grid, 14, which by the tubes, 15 and 16 is connected with the serpentines lying in the upper drums so that the tubes of the cooling grid 14, form also a part of the heat-carrier system receiving heat by radiation.

10 A superheater, 17, is arranged in the upper part of the vertical flue, 5, and a feed-water heater, 18, in the lower part, while in a rear-
ward extension of the flue, 5, an air pre-
heater, 19, is arranged.

15 Below the horizontal flue, 4, lies a passage, 20, which can be entered from the outside, this passage providing access to the tubes of the feed-water heater, 18, and to the collector header, 21, to which the tubes, 14 and 16, are connected.

20 For regulating the temperature of super-
heat a damper, 22, can be moved in the verti-
cal direction to any given position. A bridge,
23, which is preferably cooled and may con-
sist of brickwork, lies between the flues, 4 and
5, so that with the damper, 22, in the limiting
position shown in full lines in the drawings,
30 all the hot gases pass through the super-
heater, 17, while in the other limiting position
shown in chain lines, only a small part of the
gases flows through the superheater.

Both in the combustion chamber, 3, and
35 in the horizontal flue, 4, a part of the water-
heating surface, if desired, may be replaced
by superheater-heating surface.

40 It will be seen from the drawings that the
boiler described forms an organic whole and
is of a comparatively small height, these char-
acteristics and also the advantages of the
indirect method of steam generation distin-
guishing it from boilers of other kinds using
pulverized coal.

45 Although a specific form of the improved
boiler has been described for the burning of
pulverized coal, it will be seen that its main
characteristics with corresponding advan-
tages may be readily applied to the burning of
50 oil or again to the burning of coal on a grate
in the ordinary manner.

I claim:

1. In a steam generating plant, a furnace
construction comprising a combustion cham-
ber, a vertical flue having at least two super-
posed heat receiving units disposed therein,
a horizontal flue connecting the combustion
chamber with the vertical flue, a plurality of
heat receiving tubes within the combustion
chamber, said tubes being arranged to form
60 the side walls, rear wall, and roof of the com-
bustion chamber and thereby receiving heat
mainly by radiation, a plurality of tubes
arranged in said horizontal flue and thereby
65 receiving heat mainly by contact with the

hot gases of combustion, and a substantially
vertical damper member disposed between the
horizontal and vertical flues, said member
being vertically adjustable to cause the hot
gases to pass either over or under said member
70 and being arranged for movement at a height
substantially corresponding to that of the
upper heat receiving unit.

2. In a steam generating plant, a furnace
construction comprising a combustion cham-
ber, a vertical flue having at least two super-
posed heat receiving units disposed therein,
a horizontal flue connecting the combustion
chamber with the vertical flue, a plurality of
80 heat receiving tubes within the combustion
chamber, said tubes being arranged to form
the side walls, rear wall and roof of the com-
bustion chamber and thereby receiving heat
mainly by radiation, a plurality of tubes
85 arranged in said horizontal flue and thereby
receiving heat mainly by contact with the hot
gases of combustion, a transverse, horizontal
bridge lying between the vertical and hori-
zontal flues and spaced from the upper and
90 lower extremities of the vertical flue, and a
damper member vertically adjustable to cause
the hot gases to pass over or under said bridge
and being arranged for movement at a height
substantially corresponding to that of the
95 upper heat receiving unit.

3. In a steam generating plant, a furnace
construction comprising a combustion cham-
ber, a vertical flue, heat absorbing elements
in said vertical flue, a horizontal flue con-
necting the combustion chamber with the
vertical flue, a plurality of heat receiving
tubes within the combustion chamber, said
tubes being arranged to form the side walls,
rear wall, and roof of the combustion cham-
ber and thereby receiving heat mainly by
100 radiation, and a plurality of tubes arranged
in said horizontal flue and thereby receiving
heat mainly by contact with the gases of com-
bustion, the uppermost portions of the tubes
in the horizontal flue forming a roof of sub-
stantially the same height and as a continua-
tion of the roof of the combustion chamber.

4. In a furnace construction as defined in
claim 3, a chamber located between the com-
bustion chamber and the vertical flue and
below the said horizontal flue, said chamber
being formed as a passage for affording access
to portions of the heat receiving apparatus
in the combustion chamber and the vertical
flue.

110 In testimony whereof we affix our signatures.

FRIEDRICH WEMPE.
HEINRICH PEPPERKORN.
